United States Patent Office

Des. 184,638
Patented Mar. 17, 1959

184,638

LIQUID MEASURING CUP OR SIMILAR ARTICLE

Frederick W. Rettenmeyer, Meriden, Conn., assignor to
The Napier Company, Meriden, Conn., a corporation
of Connecticut

Application September 3, 1958, Serial No. 52,481

Term of patent 14 years

(Cl. D44—29)

Fig. 1

Fig. 2

Fig. 1 is a top plan view of a liquid measuring cup or similar article showing my new design; and

Fig. 2 is a view thereof in side elevation.

I claim:

The ornamental design for a liquid measuring cup or similar article, substantially as shown.
